TRAILER BODY AND CHASSIS

Billy G. Birdwell, Fort Stockton, Tex.

Application June 11, 1954, Serial No. 30,950

Term of patent 14 years

(Cl. D14—3)

Fig. 1 is a front perspective view of a combined trailer body and chassis in elevated position illustrating my new design; and

Fig. 2 is a rear perspective view thereof.

The trailer wheels and tractor are shown by means of broken lines only for purposes of illustration.

The dominant feature of the invention is the combined trailer body and chassis, illustrated in full lines.

What I claim is:

The ornamental design for a combined trailer body and chassis, substantially as shown and described.
